FOLDING MOTORIZED VEHICLE

S. Albert Young, Birmingham, Mich., assignor to Harold J. Rineman, Southfield, and Richard Lynn Rineman, Brighton, Mich., fractional part interest to each

Filed Nov. 10, 1972, Ser. No. 305,498

Term of patent 14 years

Int. Cl. D12—08

U.S. Cl. D12—1

FIG. 1

FIG. 2

FIG. 3

FIG. 4

FIG. 5

FIG. 6

FIG. 7

FIG. 8

FIG. 1 is a front perspective view of the folding motorized vehicle, showing my new design.

FIG. 2 is a rear perspective view thereof.

FIG. 3 is a front perspective view thereof, showing the front legs and wheels pivoted rearwardly.

FIG. 4 is a front perspective view thereof in its folded position.

FIG. 5 is a rear perspective view thereof in its folded position.

FIG. 6 is a front elevational view taken on line 6—6 of FIG. 1.

FIG. 7 is a rear elevational view taken on line 7—7 of FIG. 2, and

FIG. 8 is a rear elevational view taken on line 8—8 of FIG. 5, with the steering wheel and portions of the steering wheel stem being omitted for ease of illustration.

I claim;
The ornamental design for a folding motorized vehicle, as shown and described.
